(57) **CLAIM**

The ornamental design for a quilting tool, as shown and described.

DESCRIPTION

FIG. 1 is a left perspective view of a quilting tool;
FIG. 2 is a right perspective view thereof;
FIG. 3 is a top view thereof, with the bottom being a mirror image thereof;
FIG. 4 is a front perspective view thereof; and,
FIG. 5 is a rear perspective view thereof.
The broken lines in the figures form no part of the claimed design.

1 Claim, 2 Drawing Sheets
